UNITED STATES PATENT OFFICE

HUBERT R. HUMPHREY AND GEORGE A. HUMPHREY, OF KALAMAZOO, MICHIGAN,
ASSIGNORS TO GENERAL GAS LIGHT COMPANY, OF KALAMAZOO, MICHIGAN

HEATING APPARATUS

Application filed January 23, 1929. Serial No. 334,545.

Our present improvements are especially designed by us for embodiment in heating apparatus of the character illustrated and described in our application for Letters Patent filed November 3, 1928, Serial No. 314,017, and we have illustrated the same as embodied in such an apparatus. These improvements are, however, adapted and desirable for use in other relations.

10 The main objects of this invention are: First, to provide in a heating apparatus employing a burner an improved control means whereby the opening and closing of the main valve is controlled through a switch.

Second, to provide an apparatus of this character employing a pilot in which the valve opening means are rendered inoperative in the event the pilot is extinguished 20 while the main burner is not in operation, and one which does not affect the operation of the apparatus in the event the pilot should become extinguished while the burner is burning.

25 Third, to provide an apparatus of this character in which a thermally controlled switch is employed, the thermal device being arranged so that it is fully accessible at all times without disassembling the general 30 structure.

Objects pertaining to details and economies of our invention will definitely appear from the description to follow. The invention is defined in the claims.

35 A structure which embodies the features of our invention is clearly illustrated in the accompanying drawings, in which:

Fig. 1 is a fragmentary side elevation of 40 a heating apparatus embodying the features of our invention.

Fig. 2 is a fragmentary view mainly in vertical section on line 2—2 of Fig. 1.

Fig. 3 is a plan view of the cut-out switch 45 device.

Fig. 4 is a fragmentary section through the cut-out switch device, mainly in section on line 4—4 of Figs. 1, 3, 5 and 6.

Fig. 5 is a detail view mainly in vertical 50 section on line 5—5 of Figs. 2, 3, 4 and 6.

Fig. 6 is a detail section on line 6—6 of Figs. 4 and 5.

Fig. 7 is a detail section on line 7—7 of Figs. 4 and 5.

Fig. 8 is a diagrammatic view illustrating 55 the relation of the cut-out switch to the motor and main switch.

In the embodiment of our invention illustrated, we provide a base member 1 provided with a plurality of flue openings 2 in 60 its top wall 3. The burner box 4 is mounted on the under side of this base member 1 and coacts therewith to provide a closed combustion chamber 5. This combustion chamber has an air inlet 6.

The burner designated generally by the numeral 7 is arranged within the combustion chamber. Pilot burners 8 are provided for the main burner.

The flue header 9 is mounted in spaced 70 relation to the base member 1, a plurality of flues 10, preferably of relatively thin copper tubing, being arranged through the bottom 11 of the header with their lower ends projecting into the flue openings 2 of 75 the base member. The valve for the main burner is indicated at 12.

We provide a blower for supplying air under pressure to the main burner and discharging air across the flues 10 which constitute a radiating unit substantially as described in our above mentioned application for patent. The fan 13 of this blower is mounted on the forward end of the shaft 14 of the motor 15.

On the rear end of the shaft is a governor mechanism indicated generally by the numeral 16. This mechanism is operatively connected to the valve 12 by a lever 17 so that when the motor is in operation the valve is opened, or permitted to open in the event that it is opened by spring pressure as described in a concurrent application, the mechanism being preferably that described in such application.

A control or starting switch 18 is provided for the motor as illustrated in the diagrammatic view in Fig. 8. As serious results might follow in the event of the main valve being opened when the pilots are extin-

guished, we provide a cut-out switch designated generally by the numeral 19, see Fig. 8, which is controlled by a thermal device operatively associated with one of the pilots so that the thermal device acts when heated by the pilot or by the main burner to allow this switch to remain closed.

However, in the event of the cooling of this thermal device as would occur on the extinguishment of both the main burner and the pilot, the thermal device opens this switch and the switch cannot be closed until the thermal device is reheated as by the relighting of the pilot.

The thermal device is operatively associated with the radiating flue 20 which is located above one of the pilots 8 so that the heat from the pilot effectively acts upon the thermal device. This thermal switch comprises a base member 21 having an insulating block 22 mounted thereon carrying a pair of contacts 23. The movable switch member 24 in the form of an insulating block carries coacting contacts 25. The wires 26 leading from the switch 18 to the motor are connected to the contacts 23. The contacts 25 are electrically connected by the strip 27.

Springs 28 arranged on the upper ends of the bolts 29 which are passed through the base member 21 urge the movable switch member 24 to switch closing position. A cap 30 is provided for the switch members.

A tubular thermal element 31 is threaded into the base member 21 and is adapted to depend into the flue 20, it being arranged through the header as clearly shown in Fig. 2. A second rod-like thermal element 32 is secured at its lower end to a plug 33 threaded into the tube, the upper end of the rod projecting through the switch block 22 to engage a thrust member 34 on the upper switch member. This thrust member is in the form of a screw and is provided with a lock nut 35 so that it may be secured in its adjusted positions.

With the parts thus arranged, when the thermal device is unheated, the contraction of the element 31 lifts the switch member 24 against the tension of the springs 28 and thereby opens the cut-out switch. However, when the pilot is burning there is sufficient heat generated thereby to cause the thermal element 31 to expand, thereby retracting the element 32 and allowing the springs 28 to close the switch. The cut-out switch remains open as long as either the pilot or main burner is burning. The cut-out switch mechanism is arranged so that its electrical connections are not exposed to excessive heat.

The device is fully accessible at all times, is positive in operation and simple in structure. We have illustrated and described 65 our improvements as embodied in a heating

apparatus such as illustrated and described in detail in our said application for Letters Patent Serial No. 314,017. We have not attempted to illustrate or describe other embodiments or adaptations as we believe this disclosure will enable those skilled in the art to embody or adapt our improvements as may be desired.

Having thus described our invention what we claim as new and desire to secure by Letters Patent is:

1. In a heating apparatus, the combination of a closed combustion chamber provided with an air inlet, a flue header, radiating flues opening to said combustion chamber and flue header, a main burner within said combustion chamber, a pilot disposed in said combustion chamber in operative relation to said burner and positioned below one of said flues, a blower arranged to deliver air to said air inlet of said combustion chamber and provided with a motor, a main gas supply valve, a valve controlling mechanism including said motor, a cut-out switch for said motor including a relatively fixed switch member mounted on said header and provided with a pair of contacts, a movable switch member provided with coacting contacts, a spring acting to urge said movable switch member to switch closing position, a tubular thermal element mounted on said fixed switch member and depending into said flue above said pilot, a rod arranged within said tube and connected thereto at its lower end with its upper end in engagement with said movable switch member, and an adjustable thrust member on said movable switch member coacting with the end of said rod.

2. In a heating apparatus, the combination of a closed combustion chamber provided with an air inlet, a flue header, radiating flues opening to said combustion chamber and flue header, a main burner within said combustion chamber, a pilot disposed in said combustion chamber in operative relation to said burner and positioned below one of said flues, a blower arranged to deliver air to said air inlet of said combustion chamber and provided with a motor, a main gas supply valve, a valve controlling mechanism including said motor, a cut-out switch for said motor including a relatively fixed switch member mounted on said header and provided with a pair of contacts, a movable switch member provided with coacting contacts, a spring acting to urge said movable switch member to switch closing position, a tubular thermal element mounted on said fixed switch member and depending into said flue above said pilot, and a rod arranged within said tube and connected thereto at its lower end with its upper end in engagement with said movable switch member.

3. In a heating apparatus, the combina-

tion of a closed combustion chamber provided with an air inlet, a flue header, radiating flues opening to said combustion chamber and flue header, a main burner within 5 said combustion chamber, a pilot disposed in said combustion chamber in operative relation to said burner and positioned below one of said flues, a blower arranged to deliver air to said air inlet of said combustion chamber and provided with a motor, a main

10 gas supply valve, a valve controlling mechanism including said motor, means for controlling said switch including a tubular thermal element arranged through said header and depending into said flue above said pilot, a coacting thermal element arranged within 15 said tubular element and engaging one of the switch members, such switch member being provided with an adjustable thrust 20 member for said rod, and a spring acting to urge said switch member to closed position.

4. In a heating apparatus, the combination of a closed combustion chamber provided with an air inlet, a flue header, radiating flues opening to said combustion chamber and flue header, a main burner within 25 said combustion chamber, a pilot disposed in said combustion chamber in operative relation to said burner and positioned below one 30 of said flues, a blower arranged to deliver air to said air inlet of said combustion chamber and provided with a motor, a main gas supply valve, a valve controlling mechanism including said motor, means for controlling 35 said switch including a tubular thermal element arranged through said header and depending into said flue above said pilot, and a coacting thermal element arranged within said tubular element and engaging 40 one of the switch members.

5. In a heating apparatus, the combination of a combustion chamber, a flue header, radiating flues opening to said combustion chamber and flue header, a main burner within 45 said combustion chamber, a pilot disposed in said combustion chamber in operative relation to said burner and adjacent the lower end of one of said flues, and a control mechanism for said heating apparatus 50 including a switch, a spring acting to close said switch, a tubular thermal element disposed in said flue associated with said pilot and a second thermal element operatively associated with said switch arranged within 55 in said tube and operatively connected thereto.

6. In a heating apparatus, the combination with a radiating unit comprising a flue, a main burner operatively associated with said 60 radiating unit, a pilot for said main burner disposed below said flue, a main gas supply valve, a blower operatively associated with said radiating unit and provided with a motor, a cut-out switch for said motor, a 65 spring acting to close said switch, a thermal

device acting to hold said switch in open position and including a tubular element depending into said flue and suspended from its upper end, and a rod arranged within and secured at its lower end to said tubular element with its upper end in operative relation to the switch whereby heat from the main burner and the pilot acting upon the thermal device permits the closing of the switch. 70

7. In a heating apparatus, the combination of a radiating unit comprising a plurality of flues, a main burner operatively associated with said radiating unit, a pilot operatively associated with said radiating unit and with one of said flues to heat a thermal element disposed therein, a thermal element disposed in said flue, a control valve for said main burner, means for delivering a blast of air to said radiating unit including a motor, a valve control mechanism operatively associated with said motor and acting to open the valve when the motor is running, and a cut-out switch for said motor operatively associated with said thermal element. 80

8. In a heating apparatus, the combination of a closed combustion chamber, a flue header, radiating flues opening to said combustion chamber and flue header, a main 90 burner within said combustion chamber, a pilot disposed in said combustion chamber in operative relation to said burner and positioned below one of said flues, and control means for said burner including a tubular thermal element arranged through said header and depending into said flue above said pilot and a coacting thermal element arranged within said tubular element. 95

9. In a heating apparatus, the combination of a combustion chamber, radiating flues opening to said combustion chamber, a main burner within said combustion chamber, a pilot disposed in said combustion chamber in operative relation to said burner and adjacent the lower end of one of said flues, and a control mechanism for said heating apparatus including a thermal element disposed in said flue associated with said pilot. 105

10. In a heating apparatus, the combination with a radiating unit comprising a flue, a main burner operatively associated with said radiating unit, a pilot for said main burner disposed below said flue, a main gas supply valve, a blower operatively associated with said radiating unit and provided with a motor, a cut-out switch for said motor, a spring acting to close said switch, and a thermal device acting when unheated to hold said switch in open position disposed in said flue. 110

11. In a heating apparatus, the combination with a radiating unit comprising a flue, a main burner operatively associated 115

with said radiating unit, a pilot for said main burner disposed below said flue, a main gas supply valve, a blower operatively associated with said radiating unit and provided with a motor, a cut-out switch for said motor, and a thermal device operatively associated with said switch disposed in said flue.

12. In a heating apparatus, the combination of a radiating unit comprising a plurality of flues, a main burner operatively associated with said radiating unit, a pilot operatively associated with said burner and with one of said flues to heat a thermal element disposed therein, and a control mechanism for said burner including a thermal element disposed in said flue.

13. In a heating apparatus, the combination with a radiating unit, a main burner operatively associated with said radiating unit, a pilot for said main burner, a main gas supply valve, a blower operatively associated with said radiating unit and provided with a motor, a cut-out switch for said motor, a spring acting to close said switch, and a thermal device operatively associated with said pilot acting when unheated to hold said switch in open position.

In witness whereof we have hereunto set
30 our hands.

HUBERT R. HUMPHREY.
GEORGE A. HUMPHREY.
